UNITED STATES PATENT OFFICE.

EMIL J. CARROLL, OF CINCINNATI, OHIO, ASSIGNOR TO THE AMERICAN LAUNDRY MACHINERY COMPANY, OF CINCINNATI, OHIO, A CORPORATION OF OHIO.

CONTINUOUS DRYING TUMBLER.

Application filed October 7, 1921. Serial No. 506,117.

To all whom it may concern:

Be it known that I, EMIL J. CARROLL, a citizen of the United States, residing at Cincinnati, in the county of Hamilton and 5 State of Ohio, have invented certain new and useful Improvements in Continuous Drying Tumblers, of which the following is a specification.

This invention relates to drying tumblers 10 such as are used for drying garments, clothing, textile fabrics, or other materials that have been washed or subjected to cleaning operations.

The object of the invention is to provide 15 an improved drier which is continuous in operation and which enables the goods or materials to be dried to be handled in separate lots or batches thereby doing away with the necessity for individual marking 20 of each piece and adapting the drier for use in handling family washings.

Another object of the invention is to provide 25 an improved drier of this type in which the material to be dried is handled in a series of separate containers which are slowly traversed in turn through a long drying chamber and after emptying are returned to the feeding end to be sent through again with another charge. A further object of 30 the invention is to simplify and improve the mechanism for handling the containers and subjecting the material therein to the flow of a current of dry air.

Further objects of the invention are in 35 part obvious and in part will appear more in detail hereinafter.

In the drawings Fig. 1 is a side elevation partly broken out and in section, illustrating the delivery end of one embodiment of 40 the invention; Fig. 2 is a similar view of the feeding end; Fig. 3 is a sectional elevation on the line 3—3, Fig. 1; Fig. 4 is partly an elevation and partly a longitudinal section of a container; Fig. 5 is a cross section 45 thereof, on the line 5—5, Fig. 4; and Fig. 6 is a detail plan view illustrating the fan driving mechanism.

The apparatus shown in the drawings 50 comprises a relatively long narrow hollow casing 1 provided with a roof 2 and side walls 3, in one of which are a series of longitudinally spaced hinged windows 4 to enable the operator to inspect the interior of 55 the casing and gain access thereto for cleaning or repairing the mechanism. Said cas-

ing rests upon the floor or other support and is provided in its bottom with two horizontal walls 5 forming a long channel or heating chamber 5^a in which is a suitable heater, such as a series of steam pipes 6 which extend the full length of the channel and the purpose of which is to heat the air current for drying purposes. Said chamber is open to the atmosphere at one end, as at the left end, Fig. 1, and at its opposite end communicates with another longitudinally extending channel or duct 6^a beneath a curved perforated plate 6^b lying at the bottom and along the center line of the drying chamber 6^c. Above the heating coils are a series of supports 7 carrying rollers 8 on which are mounted two parallel shafts 9, shown as hollow tubes, which are inclined downwardly at a slight angle from the feeding end to the discharge end of the casing 75 and extend outwardly beyond both ends thereof. Suitable means is provided for rotating said shafts at uniform speed in the same direction. For this purpose the two shafts are provided with sprockets 10 of like size connected by a chain 11. One of said shafts is connected by gearing 12 to the motor 13 which is preferably an electric motor of the variable speed reversible type.

Spaced some distance above the shafts 9 and below the roof 2 the chamber 6^c within the casing is provided with a ceiling which includes a series of closely spaced vanes or dampers 14 each of which has a normally depending arm 15. These dampers control communication from the chamber 6^c within the casing to a series of suction chambers 17, each of which communicates by a passage 18 with the suction side of a suitable fan or blower 19. The blowers, of which any number may be used, are suitably driven in any manner, such as by being connected by crossed belts 19^a to a common driving shaft 20, driven by an electric motor 21, preferably of the variable speed type. The outlets 95 from the several fans may all communicate with a common conduit 21^a leading to the atmosphere, or, if desired, a branch conduit 21^b controlled by a damper 21^c may return all or a part of the exhausted air to the inlet 100 to chamber 5^a to recirculate it according to well known practice.

At the top of the casing is located a track or run-way consisting of two parallel angle irons 22, said run-way extending outwardly 110

- beyond the discharge end of the casing at the left in Fig. 1 and being inclined downwardly toward the feeding end where it extends out beyond the ends of the shafts 9.
- 5 The lower end of said run-way is supported by a frame 23 (Fig. 2) which also supports a curved outer track or run-way 24 which is curved in the arc of a circle around the end of the inclined run-way as a center and 10 terminates in a horizontal bottom portion 25. Said bottom portion is provided with a swinging gate 26 having two upwardly extending arms 27, the purpose of which is to release, one at a time, a series of drum like 15 containers in which the material to be dried is placed. 28 represents a table provided with a rotatable top 29 turning about a vertical axis and lying between the track and the exposed ends of shafts 9.
- 20 With the apparatus so far described are used a series of separate but like containers for the material to be dried, one of which is illustrated in Figs. 4 and 5. Each of said 25 containers comprises two cup shaped end heads or caps 30, one of which is provided with a hinged door 31 having a suitable latch 32. Said end caps or heads are connected by longitudinal re-enforcing and strengthening members 33, shown as angle 30 irons with one flange extending radially inwardly so as to serve as a baffle for turning over the material. The cylindrical wall of 35 the drum is made of wire mesh screen, as indicated at 34.
- 35 The apparatus is used as follows: In Fig. 2 a container marked A is indicated at the loading station with its door open. In this position the swinging gate 26 is turned with one of its arms 27 extending above the track 10 40 to hold back the following containers. When the container is filled it is rolled forward upon table top 29 and is turned until its axis is parallel with the shafts 9, whereupon it is slid forward into position upon 45 said shafts. The rotation of said shafts produces corresponding rolling rotation of the container and because of the slight inclination of said shafts the container has a slight tendency to and is gradually moved 50 from right to left in Figs. 1 and 2. Either the container is pushed beyond a suitable entrance door or doors 35 at the feeding end of the casing or the container is allowed to pass said doors by the progressive movement imparted to it by said shafts 9. As 55 soon as the container enters the drying chamber its upper portion engages the arms 15 of the vanes or dampers and opens communication with one or more suction chambers lying about the container. Consequently when one or a series of containers 60 are within the casing each container is subjected to the effect of a current of air coming from the heating coils and through per- 65 forated plate 6^b and flowing to the exhaust fans. Said air current absorbs the moisture and carries it away. The shafts 9 are rotated at a proper speed determined by the quantity of moisture in the goods and the speed of operation of the fans so that during 70 a single traverse of the container through the casing the material is fully dried. When the container reaches the discharge end at the left in Fig. 1 the outlet door 36 is opened and the container is removed from shafts 9 to a table 37 where it is emptied after which it is lifted to the return track 22 and allowed to roll back to the feeding end of the machine where it is brought to the working level by the 80 curved track 24, as shown in Fig. 2, and is then filled and again sent through the drier.
- What I claim is:
1. Drying apparatus, comprising a drying chamber, means for passing a container through said chamber, and additional means arranged above said chamber for returning the container to the entrance of said chamber. 85
2. Drying apparatus, comprising a drying chamber, means for passing a container through said chamber, the container being readily removable from said means, and means arranged above said chamber for returning the container to the entrance of said chamber. 90
3. Drying apparatus, comprising a drying chamber, a suction chamber above the same, a suction producing device at one side 100 of said suction chamber and communicating therewith, means for advancing containers through said chamber, and means above said suction chamber for returning the empty containers. 105
4. Drying apparatus, comprising a drying chamber, a suction chamber above the same, a suction producing device at one side of said suction chamber and communicating therewith, means for advancing containers through said chamber, means above said suction chamber for returning the empty containers, and means at the feeding end of the drying chamber for releasing the returned containers at a lower level. 110 115
5. Drying apparatus, comprising a drying chamber, a suction chamber above the same, means for advancing containers through said drying chamber, means whereby the moving containers control communication between said chambers, and a return track for said containers located above said suction chamber. 120
6. Drying apparatus, comprising a drying chamber, a suction chamber above the same, means for advancing containers through said drying chamber, means whereby the moving containers control communication between said chambers, a return track for said containers located above said suc- 125 130

tion chamber and at the feeding end of said drying chamber leading downward to the entrance thereto.

7. Drying apparatus, comprising a drying chamber, a suction chamber above the same, means for advancing containers through said drying chamber, means whereby the moving containers control communication between said chambers, a return track 10 for said containers located above said suction chamber, and means for releasing containers one by one to be fed to the drying chamber.

8. Drying apparatus, comprising a drying

chamber, a suction chamber above the same, 15 means for advancing containers through said drying chamber, means whereby the moving containers control communication between said chambers, a return track for said containers located above said suction chamber and at the feeding end of said drying chamber leading downward to the entrance thereto, and means for releasing containers one by one to be fed to the drying chamber. 20 25

In testimony whereof I hereby affix my signature.

EMIL J. CARROLL.
